UNITED STATES PATENT OFFICE.

ALFRED T. BOND, OF REXBURG, IDAHO.

MUSICAL INSTRUMENT.

No. 856,939.

Specification of Letters Patent.

Patented June 11, 1907.

Application filed January 9, 1906. Serial No. 295,309.

To all whom it may concern:

Be it known that I, ALFRED THOMAS BOND, a citizen of the United States of America, residing at Rexburg, in the county of Fremont 5 and State of Idaho, have invented new and useful Improvements in Musical Instruments, of which the following is a specification.

This invention relates to musical instruments of the stringed type, and has for its objects to provide a comparatively simple device of this character wherein the usual expensively constructed wooden body is dispensed with, one wherein the vibrations of 15 the strings will be suitably augmented in volume, and the sound waves produced in the instrument delivered in properly condensed form therefrom.

A further object of the invention is to provide a device of this character with a simple and efficient form of sounding board for properly multiplying the string vibrations, and one wherein the volume of the sound waves produced in the body of the instrument will 25 be augmented by the resonator through which they are delivered.

With these and other objects in view, the invention comprises the novel features of construction and combination of parts more 30 fully hereinafter described.

In the accompanying drawings: Figure 1 is a top plan view of an instrument embodying the invention. Fig. 2 is a side elevation of the same. Fig. 3 is a transverse section 35 taken on the line 3—3 of Fig. 1. Fig. 4 is a detail plan view of the body portion of the instrument with the sounding board removed.

Referring to the drawings, it will be seen 40 that the instrument comprises a hollow body 1 provided with a forwardly projecting neck 2 having transverse ridges or frets 3 arranged as shown to form a finger board 4, the instrument being equipped with suitable strings 5 engaged at their rear ends with a tail piece 6 and at their forward ends with string posts or 45 keys 7 and supported between their ends by a bridge 8. Coupled to the bottom of the body 1 and communicating with the interior 50 thereof is a forwardly projecting trumpet-like horn or resonator 9 through which the sound waves produced within the body are delivered from the latter, the resonator being preferably in detachable threaded engage-

ment with an externally-threaded coupling 55 member or nipple 10 secured to the bottom of the body 1.

Formed in the upper wall of the body is a pair of relatively spaced openings 11 normally closed by means of sounding members 60 or diaphragms 12 preferably composed of aluminum or other appropriate material and constituting a sounding board on which the bridge 8 rests, said diaphragms being marginally disposed between rubber or other 65 elastic packing gaskets 13 and secured in place on the body 1 by means of a metal retaining member or plate 14 in turn secured by screws or other fastening members 15, the plate 14 being seated in a recess 16 suitably 70 formed therefor in the upper face of the body, it being noted in this connection that the terminal supports of the bridge 8 are disposed respectively upon and at the centers of the diaphragms 12.

In practice, when the strings 5 are vibrated in the operation of playing the instrument said vibrations are transmitted through the medium of the bridge 8 to the diaphragms 12, which in turn increase or 80 multiply the string vibrations for producing sound waves within the body 1, from which the sound waves are delivered through the trumpet or resonator 9, it being observed in this connection that as the sound travels 85 through the resonator its volume will be augmented by the latter, as will be readily understood. Furthermore, it will be observed that the rubber packing gaskets 13 between which the diaphragms are marginally disposed will prevent direct contact of the diaphragms with the body 1 and retaining plate 14, thus to preserve the sensitiveness and 90 vibratory qualities of the diaphragm, whereby they will respond readily to the string 95 vibrations.

From the foregoing it is apparent that I produce a simple device wherein the usual expensively constructed body or box is dispensed with, one in which the string vibrations will be multiplied to a maximum through the medium of the diaphragms for proportionately increasing the sound waves within the body of the instrument, and one in which the sound waves produced within the body of the instrument are manifoldly augmented in their delivery through the resonator, it being understood that in attaining

these ends minor changes in the details herein set forth may be resorted to without departing from the spirit of the invention.

Having thus fully described my invention, 5 what I claim as new and desire to secure by Letters Patent is:

A musical instrument comprising a hollow body and a neck, said body being provided with a pair of spaced openings in its upper 10 wall and having its upper face depressed below the upper surface of the neck, a diaphragm arranged to cover the openings and constituting a sounding board, said diaphragm being of a size co-extensive with that 15 of the upper face of the body, a pair of resilient packing gaskets applied respectively at opposite faces of the diaphragm for mar-

ginally sustaining the same, strings applied to the instrument, a bridge supporting the strings, said bridge being arranged to straddle the space between the openings with its ends resting on the diaphragms respectively within the openings, a retaining plate applied to the face of the body within the depression and attached for holding the gaskets and dia- 20 phragm in place, and a resonator communicating with the body of the instrument. 25

In testimony whereof, I affix my signature in presence of two witnesses.

ALFRED T. BOND.
